OXIDATION PROCESS EMPLOYING SULFITES
OR BISULFITES

William G. Toland, Jr., San Rafael, Calif., assignor to California Research Corporation, San Francisco, Calif., a corporation of Delaware
No Drawing. Filed Sept. 25, 1958, Ser. No. 763,190
6 Claims. (Cl. 260—524)

This application is a continuation-in-part of my co-pending application Serial No. 374,426, now abandoned, filed August 14, 1953 as a continuation-in-part of my then-co-pending application Serial No. 168,849, filed June 17, 1950 (now abandoned), and relates to the oxidation of lower alkyl aromatic hydrocarbons and lower alkyl benzoic acids.

The oxidation of alkyl aromatic hydrocarbons and their partially oxidized derivatives to produce aromatic carboxylic acids having the carboxyl group or groups directly attached to a nuclear carbon atom presents the organic chemist with a delicate problem of control if high yields of the desired acids are to be obtained. If the conditions under which the oxidation is conducted are too severe, considerable losses of the charging stock are sustained by reason of ring ruptures of the aromatic nuclei. If the conditions under which the oxidation is conducted are not sufficiently severe, large proportions of the charging stock are converted to oxidation products which are intermediate between the charging stock and the desired carboxylic acids.

It is an object of this invention to provide a method by which alkyl aromatic hydrocarbons may be converted to aromatic carboxylic acids having the carboxyl group or groups directly attached to the nuclear carbon atom or atoms at high yields.

It has now been found that lower alkyl aromatic hydrocarbons, lower alkyl benzoic acids, and partial oxidation products of such hydrocarbons and acids, for example, alcohols, aldehydes, ketones, and the like, may be oxidized to produce aromatic carboxylic acids by heating a mixture consisting essentially of any of these materials, water and ammonium sulfite or ammonium bisulfite to a temperature in the range from 500° to 700° F. under a superatmospheric pressure sufficient to maintain a part of the water in liquid phase. Preferably, about 1 mol of sulfite or bisulfite per mol of methyl group to be oxidized should be used in the process of the present invention; however, those skilled in the art will recognize that other quantities will be operable. Generally, about 0.5–5.0 mols of sulfite or bisulfite per mol of methyl group to be oxidized will be satisfactory.

The nature of the reaction occurring in the process of this invention is illustrated by the following equation:

While the equation does not indicate that water participates in the reaction it is necessary to have water present and for most efficient operation it should be present in large amounts, i.e., 20 to 60 mols of water per mol of organic compound being subjected to oxidation. As indicated in the equation, the acid product is

2

present in the reaction mixture as an amide which requires a hydrolysis step to liberate the acid.

U.S. Patent No. 2,610,980 shows the employment of the Willgerodt reaction to oxidize alkyl aromatic hydrocarbons such as xylenes. In this reaction sulfur is the oxidizing agent and 3 atoms of sulfur are required to oxidize one methyl group to a carboxyl group, the carboxyl group being converted in the course of the reaction to the amide. In the process of the present invention a small amount of elemental sulfur not usually exceeding about 6% of the amount which would be required if elemental sulfur were to be provided as the sole oxidizing agent may be introduced into the reaction mixture. 2% to 10% of the amount of sulfur which would suffice to oxidize the feed if sulfur alone were the oxidizing agent may be employed. This small amount of sulfur acts as an initiator and shortens the total time required for completion of the reaction. A small amount of a water-soluble sulfide may also be used as an initiator.

20 The addition of from 0.05 to 0.3 mol of either a water-soluble sulfide or elemental sulfur per mol of methyl group to be oxidized to the reaction mixture insures rapid attainment of a high oxidation rate.

The reaction should be conducted at temperatures 25 above about 500° F. At lower temperatures the rate of reaction is low. The maximum temperature of reaction should be below the critical temperature of water in order that a liquid aqueous phase may be present in the reaction mixture. Preferably, the reaction is conducted at temperatures in the range from about 550° to 675° F., from 600° to 650° F. being optimum.

The pressure is a dependent variable in the reaction and is usually in the range from about 1000 to 5000 p.s.i.g., which insures the presence of a liquid aqueous 35 phase. The pressure may be controlled during the reaction by bleeding off a portion of the gas formed during the reaction.

The invention will be understood upon consideration of the following examples which are provided to illustrate the character of the reactions which produce the desired aromatic carboxylic acids and their derivatives, but which are not intended, in and of themselves, to mark out the limits of the invention.

EXAMPLE 1

45 7.1 g. of a technical grade of α -methylnaphthalene, 20 cc. of ammonium polysulfide-ammonium bisulfite solution, and 20 cc. of water were charged to a 250 cc. shaking autoclave. The ammonium polysulfide-ammonium bisulfite solution, with the ammonium polysulfide component being present as an initiator for the primary oxidation reaction, was prepared by suspending sulfur in ammonium hydroxide, bubbling in hydrogen sulfide, and then bubbling in sulfur dioxide; its oxidizing power was 50 such that 6 cc. of the solution were stoichiometrically sufficient to oxidize 1 cc. of xylene to phthalic acid. The autoclave was sealed, heated to a temperature ranging from 550° to 590° F., and shaken for one hour. The autoclave was cooled, depressured, and opened. The reaction product consisted of a light brown slurry and some black tarry residue. 10 g. of sodium hydroxide were added to the reaction product mixture and it was then steam stripped to remove ammonia. 200 cc. of distillate were collected during the steam stripping which were found 55 to contain 0.3 g. of unreacted α -methylnaphthalene. The stripped reaction product was filtered hot to remove tar, chilled, and filtered again. The second filtration yielded 0.4 g. of neutral light yellow crystalline material of undetermined composition. The filtrate from the second filtration was acidified to a pH 6 and filtered hot to remove free sulfur. Charcoal was added to the last-mentioned filtrate and it was refiltered, the filtrate acidified to 60

65 70

pH 2 to precipitate acids, and the acidified filtrate was filtered to separate a filter cake comprising the acidic material. This latter filter cake was washed and dried. The dry filter cake weighed 2.7 g. and consisted of α -naphthoic acid. Its neutral equivalent was 172.

EXAMPLE 2

1 mol of a mixture of meta- and paraxylene containing 85% metaxylene, 1.55 mols of hydrogen sulfide, 58 mols of water, and 1.5 mols of ammonium sulfite in the form of 1.53 mols of sulfur dioxide plus 3.08 mols of ammonia were charged to a bomb reactor which was sealed and heated to 600° F. for 60 minutes. The pressure attained a maximum of 2575 p.s.i.g. The bomb was cooled to 70° F. and depressured. The liquid product was slurried with a small amount of activated charcoal and filtered to remove color bodies. After acidification, it was found that 96.5% of the xylene feed was converted to an acid-amide mixture product having a saponification equivalent of 86 and a neutral equivalent of 101.5. After saponification, a 91.7 mol percent of mixed iso- and terephthalic acid based on the xylene converted was recovered.

EXAMPLE 3

A 2.5 liter autoclave was charged with 0.71 mol of an 85-15 ratio of metaxylene-paraxylene, 1.54 mols of ammonium sulfite, 1.55 mols of ammonium bisulfite, and 32 mols of water. The mixture was heated to 600° F. with shaking for one hour and attained a maximum pressure of 2550 p.s.i.g. Workup of the products showed the presence of 0.025 mol of unreacted xylene, 0.029 mol of toluic acids, and 0.596 mol of phthalic acids. This represents a 96.7% conversion with an 87.2% yield of phthalic acids and a 4.2% yield of toluic acid.

EXAMPLE 4

A 2.5 liter autoclave was charged with 0.707 mol of 85-15 metaxylene-paraxylene, 1.39 mols of ammonium bisulfite, 1.67 mols of ammonium bisulfite, and 21 mols of water. The mixture was heated to 600° F. for 40 minutes and reached a maximum pressure of 2300 pounds. The products were shown to contain 0.028 mol of unreacted xylene, 0.04 mol of toluic acids, and 0.518 mol of phthalic acids. This represents a 96.1% conversion with a 76.4% yield of phthalic acids and 5.9% yield of toluic acids.

The following Table I indicates the nature of the oxidation reaction with a variety of organic compounds at temperatures in the range 500° to 700° F. employing the oxidizing agent of the present invention:

Table I

Material	Reaction Product
Toluic acids.	Phthalic acids.
Caproic acid.	Carbon dioxide.
Tetrahydrofuran.	Do.
Do.	Acetic acid, succinic acid, butyric acid, CO ₂ .
Acetophenone.	Benzic acid.
Do.	Phenylacetic acid.
Cyclohexanone.	Phenol and CO ₂ .
α -Methyl naphthalene.	α -Naphthoic acid.
p-Tertiary-butyl toluene.	p-Tertiary-butyl benzoic acid.
Toluene.	Benzole acid.
Mesitylene.	Trimesic acid.
Pseudocumene.	Orthophthalic, isophthalic, and terephthalic acids.
m-Cymene.	Isophthalic acid.
Benzyl alcohol.	Benzic acid.
Durene.	Iso-terephthalic acids.
2,3-dimethyl butane.	CO ₂ , iso-butyric acid.
n-Hexane.	CO ₂ , lower aliphatic acids.

Table I—Continued

Material	Reaction Product
n-Octane.	Lower aliphatic acids (NE 75-154)
5 2,2,4-trimethyl pentane.	Trimethyl acetic acid.
2,2,5-trimethyl hexane.	Trimethyl propionic acid.
Diamyl sulfide.	Trimethyl acetic acid.
t-Butyl p-xylene.	Mixed acids, predominantly valeric acid (NE 95-110).
10 Di-isobutylene.	t-Butyl terephthalic acid.
Hemimellitene.	Trimethyl acetic acid.
Methanol.	Trimethyl propionic acid.
Trimethylamine.	Phthalic acids.
Dodecene (propylene polymer).	CO ₂ .
t-Butyl meta-xylene.	Methyl mercaptan, CO ₂ .
Sucrose.	Aliphatic acids (NE 234.8).
15 n-Butane.	t-Butyl isophthalic acid.
Benzene.	Acetic acid, CO ₂ .
Methane.	Do.
Benzylamine.	CO, CO ₂ .

The process of the present invention requires only one atomic equivalent of sulfur in the form of SO₃ to oxidize one atomic equivalent of carbon in the form of a methyl group to its corresponding carboxyl group, and only one mol of H₂S is produced per carboxyl group. In contrast, a conventional sulfur oxidation process employing sulfur and ammonia as the oxidizing agent requires the use of three atomic equivalents of sulfur to achieve the desired result, and three mols of H₂S per carboxyl group are produced, thereby necessitating larger reactor volume per unit of product, a more extensive H₂S recovery system. Further, the increased H₂S partial pressure in the sulfur-ammonia system reduces the oxidation potential and increases the difficulty in driving the reaction to completion. When employing ammonium sulfite or ammonium bisulfite in accordance with the present invention, there is materially less amide product formed than in a sulfur-ammonia system.

What is claimed is:

1. A process for oxidizing a material of the group consisting of methyl-substituted aromatic hydrocarbons and aromatic carboxylic acids having at least one nuclear hydrogen replaced by a methyl group which comprises heating a mixture consisting essentially of said material, water and an agent selected from the class consisting of ammonium sulfite and ammonium bisulfite to a temperature in the range from 500° to 700° F. under a superatmospheric pressure sufficient to maintain a part of the water in liquid phase.
2. A process as in claim 1, wherein said agent is an ammonium sulfite.
3. A process as in claim 1, wherein said agent is an ammonium bisulfite.
4. A process as in claim 1, wherein said material is a xylene and said agent is ammonium sulfite.
5. A process as in claim 1, wherein said material is a xylene and said agent is ammonium bisulfite.
6. A process as in claim 1, with the addition of about 0.05 to 0.3 mol of a sulfur compound selected from the group consisting of water-soluble sulfides and elemental sulfur per mol of methyl group contained in the material to be oxidized to accelerate the oxidation reaction.
